UNITED STATES PATENT OFFICE.

RICHARD M. PANCOAST, OF CAMDEN, NEW JERSEY.

VENTILATOR.

1,087,254.

Specification of Letters Patent. Patented Feb. 17, 1914.

Application filed May 31, 1912. Serial No. 700,692.

To all whom it may concern:

Be it known that I, RICHARD M. PANCOAST, a citizen of the United States, residing at Camden, in the county of Camden and State of New Jersey, have invented certain new and useful Improvements in Ventilators, of which the following is a specification.

The invention relates to outlet ventilators for the capping or covering of ventilating flues, shafts and chimneys, and for the ventilation of roofs of mills, factories, industrial plants, power plants, drying rooms, and all kinds of buildings, shops, roundhouses, train sheds, cars and boats.

15 The object of the invention is to provide a device which may be made of sheet metal or wood and have unusual strength, require the smallest quantity of material and the minimum of labor in construction, be storm-proof and wind-proof, have a very free delivery or outflow independent of any outside wind, and, further more, the outflow of which shall be increased by the wind from whatever direction it blows.

25 The invention objectively consists in a structure having a top, cap, hood or covering, two vertical or upright sides depending therefrom, two deflectors covering the ends of the sides, and a neck.

30 The top, cap or cover and the sides are attached directly together in any suitable way, as by riveting or reaming or soldering, when made of metal or by nailing when made of wood. The sides and the deflectors or end pieces are attached directly together in the same way, and the sides are attached directly to the neck by riveting or in any other manner. Thus there results a unity of structure made practically integral and thereby much more rigid, strong and durable than one having outstanding parts connected by arms or braces.

35 Nearly all the flues, chimneys, etc., requiring ventilator coverings have square or rectangular openings, while most all the outlet ventilators in general use are made up of curved parts with necessarily tubular or curved necks. To apply these necks to such flues and chimneys requires an additional structure, a base having its upper end tubular or circular in cross section to fit the tubular or curved necks of such ventilators, and a lower or bottom end angular in cross section to fit the angular flues or 40 openings. Now, it is obvious that my an-

50 gular make-up of ventilator-hood is particularly adapted to an angular neck and, therefore, does not need the additional connecting structure or base. But it will be seen also that my construction of ventilator-hood may readily be made with a neck of a different shape, thus doing away with the said additional connecting base when it is to fit onto a flue or chimney of a different shape.

55 There can be no covering of the straight-up unrestricted outlet of a chimney or flue that is not in itself a retarding means or hindrance to the free outflow. The only real use of the so-called outlet ventilators 60 is to keep out the elements, rain, hail, snow, cinders and down currents of outside air. Therefore, the best so-called ventilator is the one which is not only anti-ingress, but interrupts in the least degree the free out- 65 flow. Any increase of draft from any ventilator depends solely on the action of the wind, but as the wind is very irregular and uncertain in its action, and as it sometimes does not blow at all, there is no uniform de- 70 pendence upon it, and if the draft depended upon such action of the outside air the outflow would be very spasmodic. Because of the great and easy compressibility of gases the outlet of an air passageway can be 75 greatly reduced by means of a gradual taper without choking or materially retarding the outflow; but an abrupt contraction of the passageway will cause cross-currents and choking. Since a force is stronger in pro- 80 portion to its concentration, it is weakened in proportion to its being divided up. Now the nearest approach to the one-way outlet of the flue or chimney's own open mouth, and the next best is a two-way passage ven- 85 tilator or hood. The least efficient type of ventilator is one having a cone-head which intercepts, tangles up and scatters out the 90 uprising current of air or gases, thus pro- 95 ducing a retarding effect. The united force of the uprising current is received against the interrupting cone-heads and thereby more or less retarded by being spread out in thin layers in all lateral directions.

100 The routes of exit or egress in my venti- 105 lator are confined to two opposite uprising passageways in contradistinction to the spreading out in layers in all lateral direc- 110 tions of the delivery in the common cone-head ventilators.

The accompanying drawings illustrate six examples of the physical embodiment of my invention.

Figures 1 and 2, respectively, show in perspective and cross section in elevation one construction of my ventilator. Figs. 3 and 4 are similar views, illustrating a modified construction of the deflectors, and of the upper edges of the top. Figs. 5 and 6 by similar views illustrate a construction wherein the neck is a parallelogram in cross section, that is, the parallel sides are of different lengths. Figs. 7, 8 and 9 illustrate by half sectional views different modifications, Fig. 9 showing the ventilator constructed of wood.

Referring to the several figures, my type of ventilator consists essentially of two similar straight side pieces S S attached in parallel planes to two opposite sides of the neck N, two deflector parts D D attached to and covering the outer ends of the side pieces S S, and a V-shaped top T attached to the upper edges of the sides. A peaked roof or ridge-roof R may be put on the central part of the V-shaped top to guide off any snow, dirt, etc., that might otherwise collect in the angle. It is a complete outlet ventilator without the ridged or peaked roof R, the said roof being a desirable addition only to prevent accumulations of snow, ice, etc., upon the top. The V-shaped top in connection with the sides and end deflectors provide two, right and left, upward practically uniform passageways for the easy outflow of the air and smoke.

In large size ventilators, especially where the upper ends of the deflectors D are distanced far enough apart to permit a strong slanting down current of wind and rain to force itself in obliquely down on the top T, as indicated in Fig. 4 by the slanting right to left long arrow, and push some water up and over the edge, it is advisable to provide drip-edges B B at the ends of the top T to prevent any water that may thus be pushed up and over the ends A from finding its way underneath and into the neck N. The drip-edge will cause such pushed over water to fall outside the neck N, as represented in Fig. 4 by vertical short arrows. When the ventilator is made of sheet metal the drip-edges B B may be formed by bending down the upper edges of the V shaped top T, but when the ventilator is made of wood the drip-edges may be separate attachments. The drip edges are not to be proportionate with the size of ventilator, for, obviously, enough overhang to carry off any drip in a small size ventilator will do so in one, however large.

The nearly vertical arrows at the right in Figs. 2 and 4 represent the anti-ingress line. If there is an outside down current, see Fig. 6 at the left, then some wind will

enter the upper end opening between the deflector D and the end A of the top and blow on down and out the bottom opening between the neck N and the lower end of the deflector and carry by induction the outflow with it. See for illustration the bent or curved arrows at the left in Fig. 6.

The uprising arrows in Fig. 2 and Fig. 4 and at the right hand side of Fig. 6 represent the natural course of outflow under normal conditions of calm or wind.

In order that the sides S shall be as economical of metal and present as small area as possible to wind pressure, the height of the top T above the neck N should be barely enough to give free passageway to the outflow. The areas of the cross sections between the two right and left sides of the neck N and the top T may be much less than the area of the neck's cross section without choking the outflow, because of the easy compressibility of gases. The deflectors D, D, are distanced from the ends of the top T, Figs. 1 and 2, and the ends of the drip-edges B B in the other figures, and are so shaped as to provide gradually restricted upward passageways for the outflow. I have shown several shapes of deflectors which form the outer passageways, but there may be others having some advantage.

In Figs. 1, 2, 5, 6, 8 and 9 each deflector is in two planes the parts meeting each other so as to form an obtuse angle O adjacent the edge of the top T. In Figs. 3 and 4 the material is fashioned to form two obtuse angles P P. In Fig. 7 the deflector is of a general concave-convex shape.

Figs. 1 and 2 represent probably the simplest and cheapest construction, a single angle in the top T, that is, there are no bent down drip-edges at the ends A of the top T. The other examples provide against the possibility of any drip entrance into the neck N, by having turned down edges B B. Figs. 5 and 6 show an oblong rectangular ventilator, the opposite sides being parallel but of different lengths.

In Figs. 3, 4, 5, 6, 7 and 9 the drip-edges are made to lie wholly inside the discharge passages between the sides S, S.

Fig. 8 shows the upper part of the side S, cut back and notched at K so that the ends of the drip-edges of the top T may overlap the edges of the sides S, S.

Fig. 9 shows the ventilator made of wood, except the drip-edges. However, the ventilator may be constructed of any suitable material, metal or wood, or combined metal and wood.

The top T is long enough in all the examples to insure that rain and any falling matter shall fall safely outside of the neck opening. To be anti-ingress the upper edges of the deflectors are brought inward to points on a line barely passing the outer

edges A A of the top T and passing a safe distance outside of the neck opening.

From the foregoing description taken in connection with the drawings it will be obvious that I have produced a ventilator, illustrated by several examples, which fulfills all the conditions set forth as the purpose and object of my invention.

What I claim is:

- 10 1. A ventilator comprising a neck, two parallel side pieces secured at opposite sides of the neck, a top piece secured to the top edges of the side pieces and above the end 40 of the neck, and two deflecting pieces each secured to adjacent ends of the side pieces, each deflecting piece having the body thereof between the top and bottom edges extended outwardly from a plane passing through said top and bottom edges to increase the 20 open spaces between the edges of the top piece and the inner surfaces of the said side pieces; the relative location of the parts being such that a downward opening and an upward opening are provided at each side of the neck and the free edges of the top piece.
- 25 2. A ventilator comprising a neck, two side pieces secured at opposite sides of the neck, a V-shaped top piece secured to the top edges of the side pieces and above the neck 45 opening, the point of the V-shaped top piece being located above the opening of the neck and the surfaces each side of said point being inclined upwardly in planes oblique to the axis of the neck and adapted to deflect 50 the ascending currents of air to the left and right, and two deflecting pieces each secured to the adjacent ends of the side pieces; the

parts being so relatively disposed that at each side of the neck two openings are formed, one above the free edge of the top 40 piece and one below the said edge.

3. A ventilator comprising a neck, two side pieces secured at opposite sides of the neck, a top piece secured to the side pieces above the neck opening, and deflectors each 45 of a general concavo-convex shape secured at the adjacent ends of the side pieces.

4. A ventilator comprising a neck, two side pieces secured at opposite sides of the neck, a V-shaped top piece secured to the 50 side pieces above the neck opening, the under surfaces of said piece sloping upwardly to the right and left from the point of the said V-shaped piece, a roof above the top having inclined surfaces, and deflectors each 55 of a general concavo-convex shape secured at the adjacent ends of the side pieces.

5. A ventilator comprising a neck, two side pieces secured at their lower edges to the top edges of the neck and extending 60 above said neck, a V-shaped top piece with the free edges downwardly inclined and the under surfaces of said V-shaped piece extending obliquely upwardly to the right and left from the point of said V-shaped piece, 65 and deflectors each of a general concavo-convex shape secured to the adjacent ends of the side pieces.

In testimony whereof I affix my signature, in presence of two witnesses.
